DESIGN FOR A HAMMER

Andrew L. Henkel, Chicago, Ill.

Application November 6, 1944, Serial No. 116,187

Term of patent 14 years

(Cl. D93—4)

To all whom it may concern:

Be it known that I, Andrew L. Henkel, a citizen of the United States, residing at Chicago, Cook County, Illinois, have invented a new, original, and ornamental Design for a Hammer, of which the following is a specification, reference being had to the accompanying drawing, forming a part thereof.

Fig. 1 is a side view of a hammer showing my new design;

Fig. 2 is a rear perspective view thereof;
Fig. 3 is a front perspective view thereof; and
Fig. 4 is a top view thereof.

I claim:

The ornamental design for a hammer, substantially as shown.

ANDREW L. HENKEL.
